UNITED STATES PATENT OFFICE

EARL I. SPONABLE, OF NEW YORK, N. Y., ASSIGNOR TO FOX CASE CORPORATION, OF NEW YORK, N. Y., A CORPORATION OF NEW YORK

SET OR SCENERY

Application filed August 18, 1927. Serial No. 213,359.

This invention relates to certain new and useful improvements in a set or scenery for use in photography, particularly in the making of moving pictures.

It has been customary to build and paint the required set or scenery, as desired, to suit the picture to be taken, and this has required considerable space and the expenditure of a large amount of money, and the materials embodied in the scenery are practically useless after the particular picture has been taken.

Further, the manufactured painted scenery is not all that can be desired in so far as depth of picture, perspective, softness of picture by diffusion of lines and pleasing effect are concerned.

The main object of the present invention is the production of a more effective, desirable set or scenery which embodies a softness of picture by diffusion of lines, an appearance of depth to the picture, and generally a more pleasing effect by the utilization of material, the body portion of which can be re-used many times so that an improved set can be produced much more economically than heretofore.

This is accomplished by providing a peculiar and novel curtain or curtains of desired size, and formed of a material provided with a nap of substantial length, and then drawing the scene upon the nap surface of the nap fabric of the curtain with crayon, pastel, chalk or chalky material of desired color or colors.

For illustration of a suitable manufacture, I prefer to provide a curtain of velvet, black in color, and of desired size, altho other preferably solid colors, such as brown, may be used. It is essential that the fabric of which the curtain is formed, shall be one having a nap of considerable length similar to the nap of velvet so that the chalky particles will enter in among and cling to the nap to produce a diffusion of lines and a soft picture having the appearance of substantial depth and perspective.

Scenes drawn on a curtain or set of this character are exceedingly effective, as the black velvet absorbs light and does not reflect it, and no exposure comes from the unchalked portion of the curtain, the only exposure effective in producing a photographic record coming from the chalked portions constituting the scene.

In the drawings Figure 1 is a front elevation of the set of this invention.

When any one scene chalked on the curtain has served its usefulness, it is only necessary to brush the chalk from the nap of the curtain, leaving the curtain in its original plain condition of solid color, and then another scene of desired character can be drawn in chalk upon it. Thus, the curtain may be re-used many times in the production of different and very effective scenery suitable for the various pictures to be taken, and although I have described a specific construction of scenery and method of producing the same as constituting a perhaps preferred embodiment of the invention, I do not desire to restrict myself to the details of the same, as various changes and modifications may be made within the scope of the appended claims, and the term "chalk" as used in the specification and claims hereof is deemed to include any suitable drawing material such as crayon, pastel chalk, chalky materials or the like, the dry particles of which cling to the nap of the curtain.

I claim:

1. A set or scenery for motion pictures comprising a nap fabric having a scene drawn thereon with dry chalk particles which cling to and intermingle with the nap.

2. A set or scenery for motion pictures comprising a velvet curtain having a scene drawn on the nap surface thereof with dry chalk particles clinging to an intermingling with the nap.

15 3. A set or scenery for motion pictures comprising a black velvet curtain having a scene drawn on the nap surface thereof with dry chalk particles clinging to and intermingling with the nap.

10 In witness whereof I have hereunto set my hand this 8 day of August, 1927.

EARL I. SPONABLE.
